UNITED STATES PATENT OFFICE.

JOHN HENRY MEREDITH, OF ALTOONA, PENNSYLVANIA.

BRAKE.

No. 874,857.

Specification of Letters Patent.

Patented Dec. 24, 1907.

Application filed April 3, 1907. Serial No. 366,169.

To all whom it may concern:

Be it known that I, JOHN HENRY MEREDITH, a citizen of the United States, and a resident of Altoona, in the county of Blair 5 and State of Pennsylvania, have invented a new and Improved Brake, of which the following is a full, clear, and exact description.

This invention relates to brakes such as used on cars, wagons and other moving vehicles 10 for bringing them quickly to a state of rest.

The object of the invention is to produce a mechanism of this kind which is simple in construction and which will operate automatically, as it were, to compensate for the wear which takes place at the brake shoes.

While the invention is illustrated in the following specification and drawings as applied to a railway car, it is capable of use in 20 other connections, and although illustrated as a hand brake, the power for applying the brake may be derived from any other source.

The invention consists in the construction and combination of parts to be more fully 25 described hereinafter and particularly set forth in the claims.

Reference is to be had to the accompanying drawings forming a part of this specification, in which similar characters of reference 30 indicate corresponding parts in all the figures.

Figure 1 is a side elevation of an end of a car to which my invention has been applied, certain parts of the car being shown in section so as to more fully illustrate the construction of the brake mechanism; Fig. 2 is a 35 side elevation showing more in detail, certain parts of the brake mechanism; in this view a portion of the spindle of the hand wheel is broken away; and Fig. 3 is a section taken in Fig. 2 on the line 3—3 thereof.

Referring more particularly to the parts, 1 represents the car body to which my brake mechanism is applied. The truck-bolster 2 45 of the car is provided with a transverse opening 3 at which there are arranged oppositely disposed hooks 4, said hooks being attached to the upper portion of the bolster on the front and rear sides thereof, as shown. From 50 these hooks 4 hangers 5 hang downwardly, and these hangers support the brake beams 6 which are disposed in the usual manner transversely of the car, and on the adjacent sides of the wheels 7. The brake beams 6 55 are provided with brake shoes 8, which rest adjacent to the faces of the wheels 7 in the

usual manner. The hangers 5 are not attached directly to the beams 6, but are attached to brackets 9, and these brackets are provided with outwardly projecting arms 10 and 11. To these arms 10 and 11, brake levers 12 and 13 are respectively attached pivotally as shown. These levers extend upwardly and are connected pivotally by an equalizer bar 14 which extends through the 65 aforesaid opening 3.

The upper end of the brake lever 13 which is disposed adjacent to the end of the car, is pivotally attached to a hanger arm 15, which projects outwardly in a horizontal position 70 from the side of the axle. A similar arm 16 is arranged on the opposite side of the axle and opposite to the arm 15, and this arm 16 may be used where the brake is to be operated from the middle of the car instead of 75 from the end of the car, as illustrated. The upper end of the brake lever 12 is attached pivotally to a link 17 which extends toward the end of the car. This link is pivotally attached at 18 to the end of a draw bar 19. 80 The body of this draw bar 19 is bifurcated so as to present two diverging bars 20, and these bars are connected by a cross head 21 which is threaded to receive a screw 22, so that the cross head 21 constitutes a nut, as will be 85 readily understood. This cross head 21 is provided at its sides with tongues 23 which are slidably mounted in longitudinally disposed slots 24 formed in the sides of a guide bracket 25. This guide bracket 25 is attached to the underside of a bumper 26. The part of the bracket 25 in which the slots 24 are formed, constitutes a horizontal extension from the body 27 of the bracket which is attached to the under side of the bumper. 90 This body 27 comprises horizontal flanges 28 and 29 connected by a vertical web 30. Vertically through the flange 28 and seating on the flange 29, a spindle 31 passes, said spindle being rotatably mounted in suitable bearings 32 and 33 attached to the end of the car. The upper end of the spindle 31 is provided with a hand wheel 34 by means of which the spindle may be rotated, when the brakes are to be applied or released. 100

Beneath the bumper 26 and the flange 28 a bevel gear 35 is attached to the spindle, and this bevel gear is adapted to operate a bevel gear 36 which is rigidly attached to the aforesaid screw 22 in the manner indicated in Fig. 3. 110

From the construction described it will now be clearly apparent that when the hand

wheel 34 is rotated in the proper direction, the screw 22 will rotate and draw the nut 21 toward the end of the car. In this way a tensile force is produced on the link 17 and 5 the brakes will be applied. In applying the brakes, the equalizer bar 14 and the brake levers 12 and 13 operate in the usual manner, so that the shoes will be pressed simultaneously against the opposite wheels.

10 I provide an arrangement at the bracket 25 for compensating for the wear which takes place at the brake shoes, and the arrangement at this point is such that stops are presented for arresting the movement of the 15 parts when the brakes are "on" or "off", and these stops automatically adjust themselves to the condition of the brake shoes. In this way the minimum amount of movement necessary takes place, and I insure that the 20 brake shoes will always be maintained out of contact with the wheels. This latter feature is of considerable importance because where the brake shoes touch the wheels when not applied, their aggregate friction through- 25 out a long train is very appreciable. For the purpose just suggested, the nut 21 is provided on its upper side with a crown 37 or rectangular projection, and this crown is provided with a slot or groove 38 which extends 30 longitudinally of the screw 22 and in the same vertical plane with the axis of the screw, as viewed in Fig. 3.

On the end of the bracket 25 adjacent to the brakes, a transverse dog bar 39 is provided, and the upper face 40 of this dog bar 35 is inclined as indicated in Fig. 2, so that the dog bar constitutes, as it were, a tooth projecting toward the position of the spindle 31.

Resting in the slot 38 and the crown 37 40 there is provided a rack 41; this rack is provided at the nut 21 with an elongated notch 42 in its lower edge, so that abrupt shoulders 43 and 44 are formed, which may be engaged by the forward and rear faces of the 45 nut so as to limit the movement thereof. The other end of the rack which lies adjacent to the tooth 40 is provided with ratchet teeth 45, and these teeth are formed with inclined faces so that they project toward the brake 50 mechanism. This part of the rack or ratchet bar rests upon the tooth 40, and the teeth 45 are adapted to engage with the tooth or dog bar 39 so as to prevent the rack from moving toward the right as viewed in Fig. 2. The 55 operation of this rack 41 in adjusting the position of the nut 21, will now be described. Assuming the parts to be in the relation shown in Fig. 2, the brake shoes will be withdrawn from the wheels. When the brakes 60 are to be applied, the hand wheel 34 is rotated in a direction to move the nut 21 toward the end of the car; that is, toward the left as viewed in Fig. 2. This movement continues until the nut engages the stop shoulder 65 44 at the end of the notch 42. At this time

the brake shoes will have been applied to the faces of the wheels. As the shoes wear, the nut 21 will advance the rack more and more toward the left until the next notch or tooth 45 of the rack is advanced over the dog bar 70 39. In this way, as the wear on the shoes occurs, the position of the rack bar adjusts itself so that when the brakes are released or applied, the shoulders 43 and 44 will constitute suitable stops, indicating the point at 75 which the brakes are "off" or "on".

Supposing that the brakes have been very considerably worn, it is only necessary in releasing them, to move the hand wheel until the nut 21 comes against the stop shoulder 80 43. At this time the shoes will be out of contact with the faces of the wheels. In this way the mechanism adjusts itself, as it were, to the condition of the shoes, changing the position or location of the traveling movement of 85 the nut to correspond with the more or less worn condition of the brakes.

In order to adjust the brake levers to alter the position of the brake beams, the equalizer bar 14 is provided with a plurality of openings 46, and each of the levers is attached by means of a removable pin 47.

Having thus described my invention, I claim as new and desire to secure by Letters Patent:

95

1. In a brake mechanism, in combination, a link, means actuated thereby for applying the brakes, a movable member adapted to actuate said link, a stop for said movable member, and means for automatically adjusting said stop as the brake wears.

2. In a brake mechanism, in combination, a link, means actuated thereby for applying the brakes, a nut, means for guiding the same, a connection between said nut and said link for actuating said link, a member limiting the movement of said nut, and means for adjusting said member automatically with the wear of the brakes.

3. In a brake mechanism, in combination, 110 a link, means actuated thereby for applying the brakes, a bracket, a nut guided therein and connected with said link, a rack having means for engaging said nut to determine the position of travel thereof, a screw controlling 115 said nut, and means for holding said rack in a more advanced position as the brakes wear.

4. In a brake mechanism, in combination, a link, means actuated thereby for applying the brakes, a bracket, a screw mounted 120 therein, a nut guided in said bracket and connected with said link, and a rack engaging said nut and permitting a limited travel thereof, said rack having teeth projecting toward the brake and adapted to compensate 125 for the wear of the brakes, said bracket having a tooth adapted to engage the teeth of said rack to lock the same against a backward movement.

5. In a brake mechanism, in combination, 130

a link, means for applying the brakes through said link, a bracket, a screw mounted therein, a nut on said screw guided in said bracket and connected with said link, a rack engaging said nut and permitting a limited movement thereof, said rack having a plurality of teeth projecting rearwardly with respect to the direction of advance of said rack in applying the brakes, and a transverse dog bar

adapted to engage said teeth to lock said rack against a rearward movement.

In testimony whereof I have signed my name to this specification in the presence of two subscribing witnesses.

JOHN HENRY MEREDITH.
